UNITED STATES PATENT OFFICE.

FRANZ FRIEDRICH KAESTNER, OF ERFURT, GERMANY.

OIL-LAMP.

1,099,054.

Specification of Letters Patent.

Patented June 2, 1914.

Application filed January 8, 1914. Serial No. 811,042.

To all whom it may concern:

Be it known that I, FRANZ FRIEDRICH KAESTNER, a subject of the German Emperor, residing at Erfurt, Kingdom of Prussia, Germany, have invented certain new and useful Improvements in or Relating to Oil-Lamps, of which the following is a specification.

My invention relates to an oil lamp with 10 a flat wick burner.

It consists in the wick tube being twisted so that the entire width of the wick is exposed in the direction in which the beam of light is to fall.

15 The invention is particularly suitable for use in storm lanterns constructed on the regenerating system, with air supply pipes, as well as in reflectors in which the light is to be projected forward and which are provided with a reflecting mirror of any desired material. In storm lanterns constructed on the regenerating system, the two air supply pipes are carried laterally of the oil tank to the central tube above the chimney, and as a result of this arrangement the wick adjusting spindle must be so positioned that the operation of its turning button is not interfered with by the air supply pipes.

20 Consequently the adjusting spindle must be arranged at an angle to the air supply pipes, and this arrangement, owing to the spindle hitherto being arranged parallel to the long side of the flat wick tube, results in the wick being disposed at an angle to a vertical

25 plane passing through the air supply pipes, and as the wick projects the greatest amount of light from its widest surface, the greatest beam of light in such storm lanterns is not projected at a right-angle to the vertical

30 plane of the air supply pipes, but at an angle thereto. This drawback exists also in lamps provided with reflectors, in which the wick adjustment spindle is inclosed by the inner wall of the reflector. In such

35 lamps, it is impossible to adjust the regulating spindle for the wick, so that the flame of the wick tube is oblique relatively to the direction of projection of the reflector, or in other words the light does not fall with its

40 full width in the focus of the reflector and is not again projected by the same outward. This drawback is obviated in my invention by twisting the flat wick tube helically so that the upper end of the wick tube, and

45 consequently the burner cap, are in or parallel to, the plane of the air supply pipes,

or at a right-angle to the axis of the reflector, so that the light in front of the flat wick spreads in both directions and the full width of the flat wick is reflected. This arrangement of twisting the wick tube of a flat burner, has a further great advantage that the wick is automatically locked, that is to say, not shifted by any vibrations of the lamp which are transmitted to the wick spindle and have the tendency to turn it.

50 As is well known, vibrations of the lamp, or generally any shocks, produce a lowering of the wick, and for instance in the case of locomotive lamps, it is necessary for that reason to provide special locking devices on the wick adjustment spindle. Owing, however, to the flat tube being helically twisted according to this invention, and thus the wick also twisted, there is an automatic locking of the wick, and by this automatic locking, the spindle of the wick is prevented from being turned by shocks.

55 A construction of a regenerating storm lamp according to my invention with a flat wick and air supply pipes, is illustrated in 70 the drawings, in which—

Figure 1 is a front elevation, partly in section, Fig. 2 is a horizontal section on line A—B, Fig. 1, Fig. 3 is a partial longitudinal section of Fig. 1 turned through an angle of 180°, Fig. 4 shows the device on an enlarged scale in plan, with the burner hood removed and the wick tube in section, Fig. 5 is a front elevation of a lamp equipped 85 with a reflector, Fig. 6 is a vertical section of said lamp on line 6—6, Fig. 7, and Fig. 7 is a horizontal section on line 7—7, Fig. 6.

60 *a* is the wick tube of a flat burner, *b* the spindle for regulating the wick *e*, and *c* the hand wheel on said spindle. The wick *a* is twisted so that its upper open end *f* is parallel with or lies in a plane passing vertically through the air supply pipes *g*, whereby the light from the flame is projected in 90 the whole width of the wick at a right-angle to the air supply pipes forward and backward. The regulating spindle *b*, as shown in the drawing, is at an angle to the plane passing normally through the air supply 100 pipes. The same construction could be used also in lamps with flat burners and reflectors, as shown in Figs. 5 to 7, in which case the wick regulating spindle *b* disposed obliquely to the axis of the light beam of the reflector *r*, with its hand wheel *c*, is arranged 105 in the interior of the reflector. In accord-

ance with the position of the upper end of the wick or of the wick supply tube, the slot *k* in the burner cap *i* is arranged in or parallel with a plane passing through the 5 air supply pipes or normal to the axis of the reflector.

What I claim is:—

In an oil lamp having a flat wick burner, a wick tube helically twisted at its upper 10 end, so that the wick projects a beam of light from the full width of the wick, in

the desired direction, and a wick regulating spindle disposed at an angle to the upper opening of the wick tube.

In testimony whereof I have hereunto set 15 my hand in presence of two subscribing witnesses.

FRANZ FRIEDRICH KAESTNER.
